UNITED STATES PATENT OFFICE.

CHARLES LEFKOWITZ, OF NEWARK, NEW JERSEY.

CONTAINER.

Application filed March 7, 1925. Serial No. 13,673.

To all whom it may concern:

Be it known that I, CHARLES LEFKOWITZ,
a citizen of the United States, and resident
of Newark, in the county of Essex and State
5 of New Jersey, have invented certain new
and useful Improvements in Containers, of
which the following is a specification.

10 which the following is a specification.
My invention relates to improvements in
containers, such as boxes or crates, particu-
larly of the class adapted to contain and
protect fragile articles, such as bottles, my
invention being especially adapted for pro-
tecting carboys. It is particularly desirable
that carboys containing acid shall be re-
siliently supported and retained in the con-
tainers in such a way as to resist shocks due
to handling and transportation, to protect
against cracking or breaking of the carboys
and consequent leakage of the acid.

20 In carrying out my invention I provide
a container having spaced vertically dis-
posed flexible bars or dowels spaced from
the walls of the container and retained at
the opposite end for engagement with the
25 sides of a carboy or bottle in annular rela-
tion to resiliently resist lateral thrusts of
the latter, a further object being to so ar-
range the container that the parts may be
readily set up for use and the charged car-
30 boy or bottle may be inserted therein with-
out danger of cracking or breaking the
same.

My invention also comprises novel details of improvement that will be more fully hereinafter set forth and then pointed out in the claims.

Reference is to be had to the accompanying drawings forming a part hereof, wherein—

40 Fig. 1 is a side elevation, partly in section on line 1, 1, in Fig. 3, illustrating my improved container;

Fig. 2 is a cross section, substantially on line 2, 2, in Fig. 3;

Fig. 3 is a horizontal section on line 3, 3, in Fig. 1;

Fig. 4 is a detail plan view with the cover removed;

Fig. 5 is a perspective detail of one of the upper retainers for the bars or dowels; Fig. 6 is a perspective view illustrating

Fig. 6 is a perspective view illustrating a modified form of resilient bar or dowel;

Fig. 7 is a perspective view illustrating a modified form of retainer for the lower ends of the bars or dowels:

Fig. 8 is a perspective view of a modified

retainer for the upper ends of the bars or dowels, and

Fig. 9 is a side view illustrating my improved box or crate adapted to contain several carboys or bottles. 60

Similar numerals of reference indicate corresponding parts in the several views.

The body of the container, such as a box or 65
or crate indicated at 1, may be of any suitable
or usual construction adapted for carrying
goods, such as carboys or bottles 2, the same
being shown comprising side walls suitably
secured together in rectangular form, as by
nails, a strong bottom 3, and a removable
cover 4 which may be secured in place on
the sides of the container by means of nails,
the cover having an opening 4^a for the neck
of the carboy or bottle. The boards of the
sides may be close together like a box or
may be spaced apart like a crate. At 5 are
vertically disposed flexible bars or dowels
adapted to extend longitudinally along the
outer side portion of the carboy or bottle, said
bars or dowels being spaced and disposed in
an annular series substantially concentric
with the longitudinal axis of the carboy or
bottle to retain the same. At 6 are lower re-
tainers for the bars or dowels 5, which re-
tainers are located at the bottom of the con-
tainer and rest thereon. 70 75 80 85 90 95

In the form shown in Figs. 1 to 4 the retainers 6 are in the form of rectangular blocks or plates located at the corners of the container and provided with openings 90

the container and provided with openings or holes at 7 arranged in annular relation to receive the lower ends of the bars or dowels 5 for retaining the latter, which may rest against the bottom of the container, the position of the openings or 95

holes 7 being such that the inner edges of the bars or dowels bear against the outer side of the carboy or bottle when the

latter is inserted in the container. In the form shown in Figs. 1 to 4 the retainers 100

6 at the corners of the container extend under vertical corner cleats 8 which are bolted to the sides of the container.

nailed to the sides of the container and do not extend fully to the bottom nor to the cover whereby said blocks are retained in 103

cover, whereby said blocks are retained in place at the bottom corners of the container. If preferred the cleats 8 may extend to the bottom of the container and the re-

to the bottom of the container and the retainers 6 may have the corresponding corners cut out at 6^a, as illustrated in Fig. 7, 110 to match against the corresponding cleats.

Fig. 8 is a perspective view of a modified Also, instead of having separate blocks 6,

for each corner at the bottom of the container such blocks may be made in two pieces, as illustrated in Fig. 7, or in a single piece if preferred.

5 At the upper corners of the container are retainers 9 to retain the upper end of the bars or dowels 5, which retainers are adapted to fit in the corners of the container and have openings 10 to receive the upper ends of the bars or dowels. As illustrated in Figs. 4, 5, and 8 the inner edges of the retainers 9, spaced from the rectangular corners at 9^a, are curved in a circle at 9^b, substantially corresponding to the radius 15 of the openings 7 and the periphery of the carboy or bottle, and the openings 10 are so located in a circle that their inner portions open through the curved surface 9^b to admit the upper ends of the bars or dowels 5. By preference the openings 10 are slightly more than a half circle, in the nature of recesses, so that when the bars 5 are pushed laterally into said openings said bars will be retained by frictional 20 gripping of the material of the retainers 9 at the edges of the openings 10. Instead of having four separate retainers 9 in the corners of the container said retainers may be made in two pieces, as illustrated in Fig. 8, or in a single piece if preferred, provided with a central opening 11 around the margin of which opening the openings or recesses 10 are disposed. The retainers 9 rest upon the tops of the cleats 8.

30 The parts described may be readily assembled by placing the retainers 6 at the lower corners of the container, resting upon the bottom, inserting the lower ends of the bars or dowels in the openings 7 of said retainers, inserting the retainers 9 to rest upon the cleats 8, and pushing the bars or dowels 5 at their upper ends sidewise into the openings 10, and then inserting the carboy or bottle between the vertically disposed bars or dowels. Since the bars or 35 dowels 5 extend vertically in the container and along the vertical outer surface of the carboy or bottle the latter is maintained in an erect position and against lateral displacement, with lateral thrusts of the bottle and box relatively one to another, resisted resiliently by the bars or dowels serving to resist fracturing of the carboy or bottle since the bars or dowels may bend readily between the retainers 6 and 9. When the carboy or bottle is in the container and bears against the bars or dowels 5 the latter will maintain the retainers 6 and 9 from inward displacement 50 so that they will remain in position between the upper ends of the cleats 8, thereby avoiding nailing the retainers to the container.

65 In order to resiliently support and resist the weight of the carboy or bottle with-

in the container I provide resilient supports adjacent to the bottom 3 and spaced therefrom, shown in the form of bars or dowels 12, 13, arranged in series, one series extending transversely with respect 70 to the other, as indicated in Fig. 3. At opposite ends of the bars or dowels 12 are blocks 14 resting on the bottom of the container and they may be nailed thereto, which blocks have recesses 15 in their upper edges in which the adjacent ends of the bars or dowels 12 are located, which recesses are preferably slightly more than a half circle so that the bars or dowels 12 may be pushed therein to be retained frictionally. Blocks 16 are also located at opposite ends of the bars or dowels 13 and rest upon the bottom of the container, at right angles to the blocks 14, the blocks 16 being provided on their upper surfaces with recesses 17 to receive the ends of the bars or dowels 13 in manner described with respect to the recesses 15. The blocks 16 extend higher from bottom 3 than the blocks 14 so that the bars or dowels 13 are spaced above the bars or dowels 12. Said bars or dowels are flexible to resiliently support the carboy or bottle in such a manner that if the weight of the charged carboy or bottle is too great for the bars or dowels 12 they will bend to encounter the bars or dowels 13 which will resist the weight resiliently. In such a manner the carboy or bottle will be supported resiliently to resist shocks due to dropping of the 100 container.

The bars or dowels 5, 12 and 13 may be of wood in suitable cross section to resiliently resist lateral thrusts of the carboy or bottle, and each may be in a single piece, as illustrated in Figs. 3 and 4. If preferred the bars or dowels may comprise two or more complementary pieces, as shown in Fig. 6, which will provide sufficient strength with desired resiliency.

105 While the container may be arranged with a single annular row of bars or dowels 5 to receive a single carboy or bottle it will be understood that the container may be provided with any desired number of such annular series of bars or dowels, spaced apart, to accommodate several carboys or bottles, as illustrated in Fig. 9.

115 My improvement is relatively cheap to manufacture and may be shipped with the parts more or less loose within the body or container ready to be assembled for use, and will afford means for safe storage and transportation for goods, whether they be carboys or bottles or other fragile articles requiring protection against shocks and jars during transportation and handling.

120 Having now described my invention what I claim is:—

130 1. A container provided with retainers

comprising blocks located in the corners at the bottom thereof, said retainers having annularly disposed openings, retainers comprising blocks located in the corners at the top of the container provided with annularly disposed openings, and bars vertically disposed within the container and having their ends located in the corresponding openings of the retainers.

10 2. A container as set forth in claim 1, in which the openings in the top retainers open through an adjacent inner edge of each retainer.

15 3. A container having retainers located adjacent the lower corners thereof and provided with spaced annularly disposed openings, retainers located against the upper corners of the container and having curved inner edges, the last named retainers having 20 annularly disposed openings opening through the corresponding edges, and resilient bars having their ends located in the openings of said retainers.

25 4. A container having cleats at its corners, said cleats terminating at a distance from the top of the container, retainers adjacent the bottom corners of the container provided with spaced openings, retainers adjacent the upper corners of the container having their 30 inner portions resting on said cleats, said upper retainers having openings opposing

the openings of the lower retainers, and resilient bars having their ends located in said upper and lower opposing openings.

35 5. A container provided with cleats at its corners spaced from the bottom and top thereof, retainers at the bottom of the container having a portion in the corners of the container extending under the cleats and provided with means to retain bars, retainers adjacent the top of the container having portions in the corners of the container extending over the cleats and provided with means to retain bars, and spaced bars 40 extending longitudinally within the container 45 and connected to said retainers.

50 6. A container provided with retainers comprising blocks located at the lower corners of the container adjacent the bottom, said blocks having annularly disposed openings, retainers comprising blocks located at the corners adjacent the top of the container and having inner curved edges provided with openings opening through said edges, said openings being greater than a semicircle, and bars having their lower ends in the first named openings and their upper ends in the openings of the upper retainers and gripped frictionally by said retainers in said 55 openings.

CHARLES LEFKOWITZ.
